(57) **CLAIM**

The ornamental design for a nail varnish receptacle with cap, as shown and described.

DESCRIPTION

FIG. 1 is a perspective view of a nail varnish receptacle with cap;

FIG. 2 is a front elevation view thereof, with the back elevation view being identical to the front elevation view; FIG. 3 is a left-side elevation view thereof, with the right-side elevation view being identical to the left-side elevation view;

FIG. 4 is a top plan view thereof; and,

FIG. 5 is a bottom plan view thereof.

The evenly spaced broken lines are shown for the purposes of illustrating portions of the nail varnish receptacle with cap that form no part of the claimed design. The dot-dash broken lines of FIG. 5 illustrate the boundaries of the claimed design and form no part thereof.
